C. O. BRETHERRICK.
CURRENT INDUCING APPARATUS.
APPLICATION FILED JAN. 17, 1911.

1,011,313.

Patented Dec. 12, 1911.

UNITED STATES PATENT OFFICE.

CLARENCE O. BRETHERRICK, OF SEATTLE, WASHINGTON.

CURRENT-INDUCING APPARATUS.

1,011,313.

Specification of Letters Patent. Patented Dec. 12, 1911.

Application filed January 17, 1911. Serial No. 603,184.

To all whom it may concern:

Be it known that I, CLARENCE O. BRETHERRICK, a citizen of the United States of America, and a resident of the city of Seattle, in the county of King and State of Washington, have invented certain new and useful Improvements in Current-Inducing Apparatus, of which the following is a specification.

10 The present invention appertains to rotary fluid impelling or impelled apparatus embodying working vanes from which the fluid is delivered to one side of the plane of rotation, and the primary aim thereof is to 15 improve such apparatus for freer delivery of the fluid from the vanes.

The invention is further directed to an improved apparatus of the above type primarily designed for inducing currents of 20 air.

The invention resides in the novel features and combination of parts as set forth in the following description and succinctly defined in the appended claims.

25 In the accompanying drawing wherein similar reference characters designate corresponding parts throughout: Figure 1 shows in diametrical section a blowing apparatus embodying the features of my invention. Fig. 2 is a sectional end view of the same on line 2—2 of Fig. 1 with a portion of the wheel broken away.

One feature of the invention resides in providing, at one side of the wheel, as 1, a 35 suitable shield 2, which, as shown, is positioned centrally in the turned-in mouth portion 3 of a bell shaped chamber 4 and provided of circular form with a crowning surface facing the plane of rotation of the

40 wheel vanes 5. These vanes, which as will be observed are concavo-convex in cross section, extend radially from an apertured web 6 with gradually increasing width outwardly and are connected at the tips with 45 a circular rim 7 whose diameter is substantially equal to the opening in the mouth portion of chamber 4. Shield 2 is conveniently supported from a cross piece 4' of chamber 4 through the medium of a screw 50 threaded stem 2' fixed to the shield and engaged in a screw threaded aperture in the cross piece, whereby the shield may be adjusted relatively to the plane of the wheel, by imparting rotary movement to the stem.

55 Connected with stem 2', by angle gears 8,

8' is an adjusting shaft 9 journaled on cross piece 4' and provided on its outer end portion with a hand wheel 10. Stem 2' fits freely in the bore of gear 8 and is provided with a groove engaging a feather secured to the gear, which latter is provided with a peripheral groove for engagement with a pin 4'' secured to cross piece 4'.

Combined with wheel 1 is a regulator comprising a series of shut-off plates 12 secured to a ring 13 which is releasably secured, by a suitable set screw, to a hub extension of web 6 for angular adjustment to position the plates 12 over respective apertures 6' of the web, as may be desired to 70 vary the capacity of these apertures for cross currents which are induced, in operating the wheel, by interposition of shield 2 between the mouth and delivery passage 3' of chamber 4.

75 Wheel 1, as shown, is secured to an armature shaft extension 14 of an electric motor 15, mounted in axial alinement with chamber 4 on support 16, secured to said chamber.

Having thus described my invention, what I claim as new, and desire to secure by Letters Patent of the United States of America, is:

1. In apparatus of the character described, a wheel having vanes curved in cross section, a shield extending alongside said wheel and spaced from the vanes thereof, the adjacent face of said shield being convex to thereby obtain a greater spacing 90 thereof with respect to the vanes of said wheel toward its outer edge, and a chamber extending about said shield in spaced relation thereto.

2. In apparatus of the character described, a wheel having radial vanes which increase in width in an outward direction and provided with concave active faces, a chamber, and a shield arranged in spaced relation to said wheel and casing, said shield 95 having a convex face opposing said wheel.

3. In apparatus of the character described, a wheel having vanes for working fluid, a shield adjustably supported at one side of said wheel for movement toward and from the same, a chamber receiving said shield, and means for adjusting said shield including meshing gears one of which is mounted on a relatively fixed part and connected with said shield, the other of said 105 110

gears being carried by an operating shaft projecting without said chamber.

4. In apparatus of the character described, a wheel comprising a hub part and vanes for working fluid, said vanes being carried by said hub part, said hub part being formed to permit of the passage of fluid therethrough, means for regulating the flow of fluid through said hub part of the wheel, and a shield extending alongside said wheel and spaced from the said vanes thereof.

5. In apparatus of the character described, a wheel comprising a hub part and vanes extending about the same, said hub part being formed to permit of the passage of fluid therethrough, means for regulating the flow of fluid through said hub part of the wheel, a shield extending alongside said wheel, and means adjustably support-

ing said shield for movement toward and from said wheel.

6. In apparatus of the character described, a wheel comprising a hub part and vanes extending about the same, said hub part being formed to permit of the passage of fluid therethrough, means for regulating the flow of fluid through said hub part of the wheel, a shield extending alongside said wheel, means adjustably supporting said shield for movement toward and from said wheel, and a chamber extending about said shield and providing a passageway for fluid.

Signed at Seattle, Washington, this 9th day of January 1911.

CLARENCE O. BRETHERRICK.
